UNITED STATES PATENT OFFICE.

JOSEPH T. SAMUELS, OF TURTLE CREEK, PENNSYLVANIA.

WINDOW ATTACHMENT.

Application filed August 17, 1926. Serial No. 129,832.

This invention relates to builders' hardware and more particularly to an attachment adapted to be applied to a window sash and limit the extent to which a window may be 5 opened, when the attachment is in operative position.

A main object of the invention is to provide an attachment which when applied to an upper sash and adjusted to engage a 10 lower sash may not be moved out of position to engage the lower sash until both sashes are completely closed. This makes it impossible for a person to release the fastener while standing outside a window.

Another object of the invention is to so 15 construct the attachment that it may be firmly applied to an upper sash and when in place will not be unsightly.

Another object of the invention is to provide 20 an attachment of this character which may be stamped from sheet metal and therefore very cheaply produced.

The invention is illustrated in the accompanying drawings, wherein,—

25 Figure 1 is a view showing a portion of a window in elevation with the attachment applied to it, and disposed in an inoperative position.

Figure 2 is a sectional view taken on the 30 line 2—2 of Figure 1, the attachment being shown in the inoperative position in full lines, and its operative position being indicated by dotted lines.

Figure 3 is an enlarged transverse sectional view taken along the line 3—3 of Figure 2, with the attachment shown in the operative position, and

Figure 4 is a perspective view of the attachment.

40 The attachment constituting the subject matter of this invention is intended to be applied to a side stile of an upper window sash 1 and when in an operative position engages the upper edge of a lower sash 2 so that the window may be opened for 45 ventilating purposes without danger of a burglar or other unauthorized person entering a house through an open window. The bracket 3 which constitutes the mounting element of 50 the attachment is formed of strong sheet metal. The bracket fits against the side stile of the upper sash, as shown in Figures 2 and 3 and is provided with upper and lower side tongues 4 and 5 which project transversely therefrom for overlapping engagement with the inner face of the stile. A

tongue 6 is cut from the upper portion of the bracket opposite the tongue 4 and is bent to project transversely from the stile. The tongue 6 constitutes an abutment adapted to 60 be engaged by the leaf 7 and prevents the leaf from being swung upwardly and toward the glass of the upper sash beyond a substantially vertical position. Referring to Figure 4, it will be seen that the leaf 7 which 65 is also formed of strong sheet metal is provided at its free end with a side arm 8 which projects transversely from the leaf and is cut and bent to provide a lip 9 extending transversely from the arm.

70 When the attachment is applied to the window, the bracket is first placed against the stile of the upper sash a sufficient distance above its lower edge to permit the leaf 7 to be swung downwardly to the inoperative 75 position shown by full lines in Figure 2. The screws 10 and 11 are then put in place and will securely hold the bracket in engagement with the window stile. It should be noted that the lower screw 11 instead of 80 being countersunk in the bracket is formed with an enlarged head and serves, not only as means to assist in securing the bracket, but also to pivotally mount the leaf 7.

When the attachment is in place and the 85 leaf swung downwardly to the inoperative position, it does not project outwardly from the upper sash and therefore, either the upper or the lower sash may be freely opened its full extent in the usual manner. 90 When, however, the leaf is swung upwardly, to the operative position indicated by dotted lines in Figure 2, the arm 8 projects from the upper sash, as shown in Figure 3 and together with its side lip 9 extends in overhanging relation to the upper edge of the lower sash. The lower sash can then only be opened until it contacts with the arm and lip. In actual practice the distance the lower or upper sash may be opened when 100 the attachment is in an operative position is about nine inches, and will afford ample ventilation, but prevent any one from stepping into a room through the window. In view of the fact that the leaf, when swung 105 downwardly to an inoperative position, has its lower free end disposed very close to the lower end of the upper sash it will be readily seen that it can not be moved to an inoperative position until both of the sashes are 110 completely closed. Therefore a burglar would be prevented from reaching into a

room from the outside and releasing the latch. While an attachment has been shown applied to only one side of the window, it will be obvious that a similar attachment 5 could be applied to the other side thereof if so desired.

Having thus described the invention, I claim:

1. A window fastener comprising a bracket adapted to be secured against the inner side face of a side stile of an upper sash, and a leaf pivotally connected with said bracket for vertical swinging movement and provided with an arm extending transversely therefrom, said arm projecting towards the glass of the upper sash out of the path of a lower sash when the leaf is in a lowered position and extending outwardly from the upper sash into position 10 to engage the upper edge of the lower sash and limit sliding of one sash relative to the other when the leaf is swung upwardly.
2. A window fastener comprising a bracket adapted to be secured against the inner side face of a side stile of an upper sash, and a leaf pivotally connected with said bracket for vertical swinging movement and provided with an arm extending transversely therefrom, said arm projecting 15 towards the glass of the upper sash out of the path of a lower sash when the leaf is in a lowered position and extending outwardly from the upper sash into position to engage the upper edge of the lower sash and limit sliding of one sash relative to the other when the leaf is swung upwardly.
- 30

a lowered position and extending outwardly from the upper sash into position to engage the upper edge of the lower sash and limit sliding of one sash relative to the other when the leaf is swung upwardly, said arm being formed with a flat side extension having its under face flush with the lower edge of the arm and providing a wide surface for engagement by the upper edge face of the lower sash.

3. A window fastener comprising a bracket adapted to be secured against the inner side face of a side stile of an upper sash, and a leaf pivotally connected with said bracket for vertical swinging movement and provided with an arm extending transversely therefrom, said arm projecting towards the glass of the upper sash out of the path of a lower sash when the leaf is in a lowered position and extending outwardly from the upper sash into position to engage the upper edge of the lower sash and limit sliding of one sash relative to the other when the leaf is swung upwardly and an abutment extending from said bracket for engagement by said leaf to limit upward movement thereof.

In testimony whereof I affix my signature.

JOSEPH T. SAMUELS. [L.S.]
